UNITED STATES PATENT OFFICE.

WILLIAM H. WOOD, OF SOUTH EUCLID, OHIO.

LAMP.

Application filed April 25, 1921. Serial No. 444,361.

To all whom it may concern:

Be it known that I, WILLIAM H. WOOD, a citizen of the United States, residing at South Euclid, in the county of Cuyahoga and State of Ohio, have invented a certain new and useful Improvement in Lamps, of which the following is a full, clear, and exact description, reference being had to the accompanying drawings.

19 This invention relates to illuminating devices, especially such as those which are carried by vehicles, for example the headlights of automobile and trucks. The objects of the invention are the provision of a new, improved, and simplified mode and means of securing the reflector in place; the provision of a new and improved reflector which can be inserted into the reflector originally furnished with such a device in order to intensify the road illumination or to comply with local regulations; the provision of a new and improved construction of headlight; while further objects and advantages of the invention will become apparent as the description proceeds.

In the drawings accompanying and forming a part of this application wherein I have illustrated certain physical structures in which my inventive idea can be embodied, 30 Fig. 1 is a front view of a standard automobile headlight having an inset reflector containing my improvement; Fig. 2 is a vertical sectional view through the device shown in Fig. 1; Fig. 3 is a separated perspective view showing the elements of the headlight; Fig. 4 is a front view and Fig. 5 a sectional view showing one mode of securing the inset reflector upright in the absence of a dimmer-bulb; Fig. 6 is a central sectional view showing my invention as applied directly to a lamp casing, the casing also being constructed in accordance with my improvements; Fig. 7 is an enlarged detail view showing the mode of securing the lamp ring to the case; 45 and Fig. 8 is a detail view of part of the locking hoop.

Describing by reference characters the parts shown in Figs. 1 to 3 inclusive, 1 represents the lamp casing which is generally of substantially hemi-spherical form having at its open end the inturned flange 2 which is provided at spaced points with circumferential hooks 3, and beneath these hooks with springs 4 pressing outwardly against said hooks. 5 represents the original or standard reflector whose mouth is provided with

a sealing cord 6 outside of which is a flange 7 formed with spaced notches 8 adapted to permit the passage of the hooks 3. This reflector is held in place by being applied to the mouth of the housing so that the hooks enter the notches, and then turning the same so that the flange is caught beneath these hooks. 9 represents the glass pane or lens which is held against the cord 6 by the inwardly projecting lip 10 of the ring 11 which fits snugly over the mouth of the housing and is provided interiorly at spaced points with hollow rectangular boxes 12 which also engage the projecting ends of the hooks 3 whereby all the parts are held in place. The springs 4 press the reflector rim against the inner walls of the boxes, and the latter against the inner faces of the hooks, thereby preventing either rattling or disengagement. Slidably mounted in the vertex of the reflector is a lamp socket 13 having a screw-threaded arm 14 connected to an adjusting screw 15 by which the lamp 16 can be focused; and the upper part of the reflector is also provided with a second socket 17 adapted to receive the dimmer-bulb 18.

The foregoing is standard construction with many lamp concerns, and one object of the present invention is the provision of an insert reflector which can be introduced and secured inside the reflector 5 without any modification of the device or interference with the features already present. Such an addition is sometimes desirable for the purpose of hiding a rusted or unsightly original reflector or for securing a measure of light control as required by many ordinances and also desired by many drivers. This invention has been designed particularly to facilitate the employment of reflectors of the type shown in my Patents Nos. 1,235,275 and 1,235,276, but is not restricted to any particular reflector construction except as defined in my claims. The expression "bowl-shaped" is intended to cover all varieties of concave reflector, whether paraboloid, hyperboloid, spherical, warped, or composite.

20 represents such inset reflector. Its heel is provided with an aperture 21 for the lamp socket and also preferably with a pad or spacer 22 adapted to rest against the heel of the reflector 5, and its mouth is provided with a circular flat flange 23 adapted to enter the mouth of the reflector 5. In case the reflector 5 is provided with a special dim-

mer-bulb the reflector 20 is also provided with a hole or slot 24 to accommodate the same. In order to hold the inset reflector tightly in place suitable spring devices are 5 interposed between it and the glass pane or lens whereby it may be forced yieldingly into the original reflector, and other yielding devices are disposed around the edge of the flange 23 to center the same. I have 10 shown three small leaf springs 25 carried by the forward face of the flange 23 and engaging the glass, and other small springs 26 carried by the edge of this flange and engaging the main reflector. I have shown 15 the springs 25 and 26 as formed from the same thin-metal clips which are rigidly riveted to the reflector, this being the simplest and cheapest construction, though not the only one as they can obviously be made 20 separately. The stiffness of the springs 26 is preferably less than that of the members 25 since it is imperative that the reflector be forced completely to its seat which might not occur if the conditions were reversed. 25 These springs are preferably located so as to be concealed by the ring 10.

I have shown the flange 23 as of variable width, although the use of my invention is not limited to such a condition. However, 30 most light controlling reflectors are warped or asymmetrical in some way and require to be applied and maintained in a given position. When a dimming bulb 18 is employed the same establishes and maintains this position of the reflector; when no such device is present other means are employed, for example that shown in Figs. 4 and 5. The body of the clip which carries the springs 35 25 and 26 is offset from the flange 23 to provide a narrow socket adapted to receive the shank 30 of a thin metal member having 40 a hooked end 31. The side of the flange which is uppermost is provided with one of these clips, and the cord 6 is pried 45 out of its groove at this point sufficiently to receive the hook portion, after which the parts are assembled as shown.

In case the distance between the two reflectors is too great to be bridged by the 50 usual socket an extension socket 33 may be employed for either or both the main bulb and dimmer bulb.

My invention is not limited to the insertion of one reflector into another but may 55 be utilized in the connection of a reflector into the lamp shell, especially in case the glass securing means be designed to conform thereto. For example in Figs. 6, 7, and 8, the reflector 20, is provided with the 60 same springs 25 and 26 and flange 23, but is inserted directly into a shell 35 whose mouth is formed with an out-turned flange 36 formed on its forward side with a seat for a sealing cord 37 and at its rearward 65 side with a slanting wall 38. A glass pane

39 is held yieldingly against the sealing cord by a hollow ring 40 which surrounds it and is provided with a front flange 41 which engages the glass and a rearward flange 42 which overlaps the flange 36, and 70 defines an opening through which said flange may pass. Between said last flanges I interpose a contractile hoop 43 having at one point a pair of radial fingers 44 which project through the narrow space between such 75 flanges where they are accessible for intentional operation but shielded from accidental actuation.

The contraction of this hoop combined with the slanted surface 38 draws the glass 80 tightly against the cord 37 and seals the entire lamp interior. The contraction of this hoop can be enhanced by the application of a spring 45 if desired, though it is not generally necessary. The springs 25, engaging 85 the glass, force the reflector rearwardly to a solid seat provided therefor, such as the tube 46 rigidly secured to the shell and having the lamp socket 47 slidably secured therein by the joint action of the spring 90 48 and screw 49. The heel of the reflector is formed with a hole snugly securing the lamp socket which therefore holds the parts in line. 50 represents a washer which may be interposed, either for wearing, cushioning, or spacing purposes. 95

It will be noted that in both the structures here illustrated a sealed casing is provided for the entire reflector and that reflector is held in place by the same part 100 which holds the glass pane or lens, thus providing a peculiarly cheap and simple structure. By the language "bowl-shaped receiving member" I include both constructions and all modifications thereof. The reflector is also thrust rearwardly toward a rigid seat which is fixed relatively to the light source, thus providing for a firm and unchanging focus. There are no parts which can get loose, or rattle, no soldered joints 105 are employed, and in the case of the complete headlight here described, the device is simple, cheap, and made of few parts. It will be understood that I do not limit myself to the structures or details herein 110 set forth except as specifically recited in my claims.

Having thus described my invention what I claim is:

1. A reflector for headlights having a flange at its open end, a metal spring carried by the forward face of said flange adapted to engage the glass of the headlight in which it is placed, and a plurality of laterally projecting metal centering devices 115 spaced around such open end.

2. A reflector for headlights comprising a bowl-shaped member having an aperture at its vertex and a circular flange about its rim, a plurality of spring devices 120

ried by the forward face of said flange, and a plurality of yielding centering devices spaced about the edge of said flange.

3. In a lamp, in combination, a bowl-shaped receiving member, a lamp socket carried by the heel thereof, a bowl shaped reflector having a hole in its heel adapted to receive said socket, means for centering the open end of said reflector in said receiving member, rigid spacing means between the heels of said member and bowl, and means for yieldingly pressing said reflector into said receiving member.

4. In a lamp, in combination, a bowl shaped receiving member, a transparent closure sealed to its open end, a lamp socket carried by the vertex of said member, a bowl shaped reflector having in its heel a hole for said lamp socket and having at 20 its mount a rim adapted to fit inside said receiving member, spring means interposed between said rim and closure whereby said reflector is seated, yielding means interposed between said rim and receiving member 25 whereby said reflector is centered, and means for holding said reflector against rotation.

5. An insert reflector for headlights comprising, in combination, a bowl shaped member adapted to be introduced inside the 30 original reflector, the heel of the bowl being apertured for the lamp socket, means carried by the mouth of the bowl for centering it in the original reflector, and spring means adapted to engage the lamp-closure and seat 35 said insert reflector against the heel of the original reflector.

6. A reflector for headlights comprising a bowl shaped member having a hole at the bottom and a flange around its mouth,

spaced springs carried by the said flange 40 and facing forwardly and yielding members also carried by said flange and facing laterally.

7. A reflector for headlights adapted to be introduced inside the original reflector 45 and comprising a bowl-shaped member having a hole at its bottom adapted to receive the original lamp socket and a continuous circular rim around its mouth, and metal leaf springs carried by the forward face 50 of said rim to engage the headlight glass and press said inset reflector into the original reflector.

8. In a headlight, in combination, a bowl-shaped receiving member, a bowl shaped 55 reflector therein, a transparent closure traversing the open mouths of said member and reflector, a closure-securing device acting to draw said closure toward said member, means for sealing the joint between said receiving member and closure and metal 60 springs interposed between said reflector and closure acting to force said reflector away from said closure.

9. In a headlight, in combination, a bowl shaped receiving member having a groove around its mouth, a cord in said groove, a transparent closure making sealing contact with said cord, a bowl-shaped reflector inside said receiving member having a hole 70 at its vertex and a circular lip around its open mouth, and metal springs carried by said lip and engaging said closure whereby said reflector is forced away from said closure and centered and held in place. 75

In testimony whereof, I hereunto affix my signature.

WILLIAM H. WOOD.
